UNITED STATES PATENT OFFICE.

HANS LUNDQUIST, OF CHICAGO, ILLINOIS, ASSIGNOR TO UNITED STATES SPECIALTY CORPORATION, OF CHICAGO, ILLINOIS, A CORPORATION OF ILLINOIS.

LACE-THREADING MACHINE.

Application filed April 23, 1921. Serial No. 463,829.

To all whom it may concern:

Be it known that I, HANS LUNDQUIST, a citizen of the United States, residing at Chicago, county of Cook, and State of Illinois, have invented a new and useful Improvement in Lace-Threading Machines, of which the following is a specification.

This invention relates to improvements in machines for inserting a tape or thread into the mesh of lace.

It is an object of the invention to provide in combination with means for alternately lifting and lowering portions of the lace relatively to a threading needle, other means whereby the transverse strands of the lace are impacted and are pushed onto a point of the threading needle on which the tape is placed.

It is also an object of the machine to unite with a prime mover means for imparting forcibly a vertical reciprocating movement to gripping shoes between which the lace is yieldingly held, whereby portions of the lace are alternately brought above and below the plane of the needle.

It is furthermore an object to provide in combination with the prime mover of the machine means for imparting a reciprocating movement to feeding pins, whereby these pins are alternately advanced towards the gripping shoes and removed from the same; the feeding pins being at the same time, however, reciprocated or oscillated in a plane at right angles to that of the lace so as to enter the mesh of the lace and to advance the same in direction of the needle.

It is therefore also an object to provide a feeding device in which a pin is forced to travel through an approximately elliptical path, for feeding a portion of the lace while traveling through one part of this elliptical path, and for returning to another point of the lace after traveling in a path out of engagement therewith.

It is also an object of the invention to provide in a device of this character a pair of feeding pins which travel in opposite direction at the same time so as to accelerate the feeding movement of the lace with respect of the needle. Whenever one of the feeding pins exerts a pull upon the lace to force the same onto the needle, the other pin will move in opposite direction to enter into engagement with a different portion of the lace.

The invention also contemplates the provision of means for arbitrarily selecting the length of the feeding step without altering the rotary movement of other parts or the reciprocating movement of the gripping shoes in the machine.

The invention also contemplates the provision of means for automatically moving the support of the feeding pins to inoperative position when released, and the provision of a transmission between the supports of several feeding pins, whereby upon movement of one support to operative position the other support also is moved to the same position, and vice versa.

With these and numerous other objects in view an embodiment of the invention is illustrated in the accompanying drawing and described in the following specification, the novel features being pointed out in the appended claims.

In the drawings:

Fig. 1 is a front elevation;

Fig. 2 is an end elevation viewed from the right hand end of Fig. 1;

Fig. 3 is a top plan view on a slightly smaller scale;

Fig. 4 is a sectional view of frame elements taken on line 4-4 of Fig. 3 and showing the parts on a slightly larger scale;

Fig. 5 is a vertical sectional view on lines 5-5 of Fig. 1;

Fig. 6 is a sectional view on lines 6-6 of Fig. 3;

Fig. 7 is a horizontal sectional view taken through the structure of Fig. 6;

Fig. 8 is a vertical central sectional view through a gripping shoe on a slightly larger scale;

Fig. 9 is a sectional view on line 9-9 of Fig. 2; and

Figs. 10, 11, 12, 13, and 14 show details of the apparatus in different stages of an operative cycle.

The entire machine may be mounted on a base plate or frame 1, on which also a motor 2, forming the prime mover of the machine, is fixedly supported. A bearing structure 3, also secured to the base plate, carries, as may be seen in Fig. 5, two parallel shafts 4 and 5, which are rotatably secured in the standards 6 and 7 of the structure. The upper shaft 4 is equipped at the projecting end with a gear 8, having teeth slanting in opposite directions, or with some gearing,

- permitting of considerable reduction of speed. This gear 8 on the shaft 4 receives its drive from a similarly constructed pinion 9 on the shaft of the motor 2; the reduced speed of the shaft 4 is transmitted to the shaft 5 through a gear 10, mounted on the other end of the shaft 4 in mesh with a gear 11 of equal diameter, fixedly secured to the corresponding end of the shaft 5.
- 10 The shaft 5 carries at the other end a bevel pinion 12 secured to a reduced portion of the shaft, and in driving relation with a longitudinally disposed shaft 13, Fig. 3, which is supported at its front end on a bearing bracket 15 and which may be supported on the other end in some suitable way not shown in the drawing.
- 15 The rear end of the shaft 13 has a bevel gear 14 in engagement with the bevel gear 12 of shaft 5, and the front end projecting beyond the bearing bracket 15 carries a crank disc 16 on which a crank pin 17 is eccentrically secured, Fig. 2.
- 20 A lever 18, having a pivotal support 19 on top of a bracket 20, has a bifurcated rear end 21, which embraces the crank pin 17, the depth of the bifurcated portion being sufficiently large to permit of the rotary movement of the pin 17 and to cause at the same time the oscillation of the lever 18 about its pivot 19. A transverse head is secured at the end of the bifurcated portion 21, as indicated in Fig. 2, to prevent accidental displacement of the lever and the crank pin 17.
- 25 The opposite end of the lever 18 is also bifurcated, as shown at 22, Figs. 2 and 6, and embraces a transverse pin 23, which is secured between rearward lugs 24 of a cross head 25 guided in a vertical standard 26. In order to permit of an exact adjustment of this standard 26, it is placed between lugs 27, Fig. 6, which rise from the base plate 1; holding plates 28 are secured on top of the lugs 27 by means of screws 29, whereby these plates may be clamped against the foot of the standard to retain the same in adjusted position. Pressure screws 30, which extend through the foot of the standard 26, may serve for increasing the clamping effect produced by the plates 28 on the lugs 27. This standard, as will be seen from Figs. 1, 2, 6 and 7, is provided with lateral vertical guideways 31, into which the lateral extensions 32 of the cross head 25 project. Displacement of the cross head forwardly or rearwardly is prevented by the ribs 33 of the standard and by the plates 34, which are secured to the front face of the standard.
- 30 The cross head 25 is also provided between the top and bottom surfaces of the same with a projection 35, Fig. 6, in which a rock shaft 36 is rotatably supported. The cross head, furthermore, is provided with a vertical bore
- 37, which communicates with that cavity 38 into which the rock shaft 36 projects. The inner end of the rock shaft 36 carries a bevel gear 39 in engagement with a bevel gear 40 at the lower end of a vertical rock shaft 41 supported in a sleeve 42, the reduced portion 43 of which is fitted into the bore 37 of the cross head. The rock shaft 41 is fixed against rotation with respect to the sleeve 42, as shown in Fig. 6, and projects beyond the sleeve. To the projecting end a crank 44 is fixed, and the free end of this crank is integral with a vertical extension 45 having a central bore and an outer thread. A holding pin 46 is slidably secured within the bore of the crank 44, and the reduced portion 47 of this pin is surrounded by a spring 48 in the interior of the extension 45, this spring resting at one end on a shoulder of the pin and being forced thereby against the closing surface of an adjustable cap nut 49 which rides on the threaded outer surface of the extension 45. That end of the pin 46 which projects through the cap nut 49 is threaded and carries a nut 50 whereby the downward movement imparted to the pin 46 by the spring 48 may be limited.
- 40 A bracket 51 is secured to the rear surface of the cross head 25, Fig. 6, and carries at its top a lateral arcuate extension 52, Fig. 3, having a plurality of sockets 53 into which the end of the pin 46 may enter to lock yieldingly the crank 44 and hence also the shaft 41 against rotation with respect to the cross head. If it is desired, however, to adjust the crank 44 in order to rock thereby the shaft 41, it is only necessary to lift the pin 46 against the tension of the spring 48, whereupon the crank may be rotated to the desired extent. It may then again be yieldingly locked in its new position by permitting the pin 46 to enter a different one of the sockets 53.
- 45 The part rotation which is imparted manually to the crank 44 is transmitted through the bevel gears 40 and 39 to the shaft 36. This shaft, as may be seen from Figs. 2 and 6, carries at its free end a rigid extension 54, which terminates in a knob or shoe 55. An annular projection 56 of the sleeve 42 supports rigidly a rod or bar 57, which is pinned to the projecting portion. The free end of this bar 57 also is in rigid connection with a tubular elbow bracket 58, as illustrated in Figs. 6 and 8, in which another gripping shoe 59 is yieldingly held and forced normally into engagement with the companion shoe 55 through a spring 60 in the vertical tubular arm of the bracket 58, this spring resting at one end at the bottom of the bore and at the other end against a shoulder 61 on an enlarged portion 62 of a stem 63 with which the shoe 59 is united. The extension of the stem 63 is threaded and projects be-

yond the vertical arm of the tubular bracket. To vary the resiliency of the spring 60 a set of lock nuts 64 rides on the threaded extension of the stem 63. The spring 60 has 5 a tendency to force the shoe outwardly, the outward movement being limited by the engagement of the lower one of the nuts 64 with the top end of the vertical tubular arm on the bracket. Rotary movement of the 10 stem 62 about its axis is prevented by a pin 65 projecting from the same into a vertical slot 66 of the bracket 58.

When the crank 44 is turned about the 15 axis of the shaft 41 the gripping shoe 59 also will be turned about the same axis, and at the same time the gripping shoe 55 will be turned about the axis of the shaft 36, that is, about an axis extending at right angles to that about which the shoe 59 is rotated, Fig. 10.

By the rotation of the shaft 13 an oscillating movement is imparted to the lever 18 and a reciprocating movement is thereby transmitted to the cross head 25, and hence also to both of the gripping shoes 55 and 59, which are yieldingly held in contact through the spring 60.

The standard 26 also carries a bracket 67, Fig. 1, projecting laterally from the same, and supporting at its outer end a clamping shoe 68, on which the threading needle 69 is removably supported. This bracket 67, as will be seen from Fig. 3, supports the clamping head 68 through a relatively long 30 arm 70, which projects at right angles to the plane of the bracket.

The main body of the needle 69 is of known construction. It consists of a relatively straight shank 71, the end of which is embraced by a clamping ring 72, held in 40 adjusted position by a set-screw 73. The shank 71 emerges into a loop 74 of approximately helical shape, Fig. 3. The end of this needle is in detachable connection with a needle point 75, preferably made of a flat piece of metal, (Fig. 1), and this point has a relatively long eye 76. This threading needle has longitudinal grooves 78 in which one or more tapes or threads may be inserted, the 50 portions of this tape or thread being guided by the clamping ring 72 and partly by a clip 77 located near the connecting end of the needle point and bridging the longitudinal grooves. The front ends of these grooves have laterally deflected portions 79 to assist in retaining the ends of the tape or thread in position, and to prevent an accidental withdrawal of the same.

While in lace threading machines of 60 known construction the advance or feeding movement of the lace ordinarily is effected by rollers contacting the lace from opposite sides and frictionally pulling the same through between the gripping shoes, the present invention provides means for posi-

tively feeding the lace in a step by step movement, at the same time permitting of a variation of this feeding step in accordance with the character of the lace. The mechanism, Figs. 1, 3, 4, and 5, for effecting this 70 step by step positive feeding movement of the lace, includes two substantially similar quadrilateral frames 80 and 81, respectively, each rockably supported through hubs 82 on the shafts 4 and 5, respectively. Each of 75 these frames or yokes consists of the two parallel longitudinal arms 83 and of the transverse arms 84; the upper frame 80 furthermore has a forward extension 85, to which a chain 86 is connected. A pin 87 80 projects from the front of the upper yoke 80 against the lower yoke, to limit the distance to which the front ends may approach each other, Fig. 4. The rear ends of the 85 two frames, however, on the other side of the shafts 4 and 5 are yieldingly interconnected by springs 88, which are attached at their lower and upper ends to pins 89, projecting from the arms 83 outwardly, Fig. 3.

One hub 82 on each frame has a gear 90 sector 95, the sectors being in mesh, whereby, upon a pull upon the chain 86 a swinging movement downwardly is transmitted to the upper yoke 80, and at the same time the other yoke is, owing to these sectors, swung 95 upwardly (against the tension of the springs 88), until contact of the pin 87 with the lower yoke stops this movement. Upon release of the chain 86 both frames are pulled 100 apart at their front ends by the springs 88.

Each of the frames 80 and 81 carries at 105 one of the longitudinal arms a rock shaft 90 extending transversely between the arms 83 and beyond the same. This rock shaft 90 in each frame is rigidly connected through the hub 96 with an arm 91, which carries a roller 92 engaging a cam groove 93 in the discs 94, which are keyed to the shafts 4 and 5, respectively. Both of these arms 91, therefore, are under the control of the cams 110 94 and the shafts 4 and 5, whereby the shafts 90 will be oscillated.

Fig. 5 clearly shows that the arrangement 115 of the discs 93 on the two shafts is very compendious and permits the entire structure to be crowded into a relatively small space, the arms 91 on both of the shafts being approximately in the same vertical plane and having the rollers 92 oppositely directed to enter the cam grooves 93 of the 120 pertaining cams 94. If the yokes 80, 81 are converted into a rigid structure (Fig. 4), through a pull on the chain, the rotation of the cams 94 will cause oscillation of the rock shaft. But if the chain is released 125 and the frames are yieldingly supported, owing to the action of springs 88, the rotation of the cams will merely cause the frames to oscillate about the shafts 4 and 5, respectively. 130

The rock shafts 90 carry each at their free ends a sleeve 97 which is pinned thereto and which extends at right angles to the axis of the shafts 90. The sleeves 97 will, therefore, also be rocked about the axis of the shaft. The sleeves have lateral tubular extensions 98 through which they are fastened to these shafts 90, the latter being advisably supported in bearing lugs 99, which project from the longitudinal frame parts 83, Fig. 3.

The sleeves 97 each serve for slidably supporting a rod 100, and these rods have at their forward ends angular arms 101, terminating in oppositely directed pins 102 and 103, respectively. Those ends of the angular arms 101 which are secured to the rods 100 are threaded, whereby a longitudinal adjustment of these arms is made feasible and each arm may be held in adjusted position by a lock nut. The rods 100 which support the pins 102 and 103 respectively being oscillated by the enforced oscillation of the sleeves 97 it is obvious that the pins 102 and 103 are also oscillated up and down, or rather in the arc of a circle having its center in the axis of the pertaining rock shaft 90.

The pins 102 and 103 terminate in reduced extensions 104, which enter the mesh of the lace and then again recede from the same. Means are also provided for longitudinally reciprocating these pins 102, 103 whereby the lace is fed, owing to the impact or push of the extensions 104 against strands of the lace. This is accomplished through means which longitudinally displace the rods 100 for the feeding pins.

The rear ends of these carriers or rods 100 are equipped with heads 105, which are bifurcated, as indicated at 106 in Fig. 3. Crank rods 107, terminating in flat eye portions 108, are pivotally connected with these heads, and the opposite ends of the crank rods 107 are detachably connected with crank pins 109.

The crank pins, as may be seen from Fig. 1, are mounted on slides 110, which are movable in guideways 111 on the discs 112, keyed to the shafts 4 and 5, respectively, and which are also associated with the gear wheels 10, 11, Fig. 5.

The guide-ways of these discs are partly covered by segmental plates 113, which can be clamped against the faces of the discs 112 by the screws 114. When properly clamped in position they will retain the slides 110 immovably in the adjusted position, whereby the throw or stroke of the pins 102 and 103 may be selected arbitrarily not only as to length, but also as to timely relation with the companion pin.

The operation of the device will become apparent from the above description. The various steps, which are repeated with great

speed whenever the engine is in operation, are illustrated in Figs. 11 to 14, inclusive. If it is desired, for instance, to insert a tape T into the lace L, this tape is placed on the needle 69 so as to be presented to the lace 70 in the shape of a spiral loop, the free end of the tape being secured on the needle by the clip 77, which bridges the grooves near the front end of the needle. The two gripping shoes 55 and 59 are then swung to inoperative position by rotating the crank 44 after the yielding locking pin 46 has been released from the pertaining socket 53, and in this released position the shoes 55 and 59 are also held locked by permitting this pin 46 to enter another socket of the arcuate extension 52 on the bracket 51. In order to prevent rotation of these gripping shoes 55 and 59 in a predetermined direction the shaft 36 of one of these shoes carries a pin 85 115, which, as will be seen from Fig. 1, is held against rotation in a certain direction by a pin 116 projecting from the face of the cross head 25. The chain 86 is released permitting the springs 88 to pull the yokes 90 apart at their front ends so that the feeding pins also occupy the position indicated in Fig. 10.

The lace is then placed with its end on the eye piece 75 of the needle, and the shoes 55 and 59 are returned into the position in which they are shown in Figs. 11 to 14. This is the operative position of the two shoes in which they grip the lace and alternately move the same, owing to vertical reciprocating movement of the cross head 25 above and below the eye piece 75 of the needle.

When then the operator depresses the treadle (which is not shown), the feeding pins 102 and 103 are also moved towards each other in a vertical plane, so as to occupy approximately the position illustrated in Fig. 11, and it will be understood from a reference to this figure and reference to Fig. 1 that the extensions 104 on these pins are not in direct opposition to each other, the crank pin 109 for the lower pin 103 being, for instance, at the left side of a vertical line which extends through the axes of the pertaining crank discs, while the upper crank pin 109 is at the right side of the same line. The pin rods 100, therefore, do not project to the same extent from their sleeves 97 and it will also be obvious that in the continued rotation of the crank discs 112 a similar relation of the feeding pins will be maintained. These feeding pins, therefore, will each move in a substantially elliptical path, produced by the combination of the movement due to the oscillation of the sleeves 97 and the movement of the crank pins 109. While traveling each through this approximate elliptical path, the pins will move oppositely to each other; one pin, as for 120 125 130

instance, 102, moving in direction towards the needle 69 when the other pin 103 is moving in direction towards the lace, as indicated at Fig. 12. As a result of this alternate or "walking" pin movement, the pin 102 in impact with a strand which has been placed above the needle point 75, will feed this lace forwardly from the position shown in Fig. 12 to the position shown in Fig. 13, and the other pin 103 will then enter into similar relation from below with respect to a strand which has been placed below the needle. The upper pin then returns, as shown in Fig. 14, while the lower pin causes the advance of the lace. This play is repeated very rapidly until an entire length of lace is fed on the needle.

I claim:

1. In a device of the character described, the combination of a threading needle and means for feeding lace on the needle, said means including elements which successively engage in alternation from above and below portions of the lace to be fed, and means for imparting an oscillating and reciprocating movement to said elements.

2. In a device of the character described, the combination of a threading needle and means for feeding lace on the needle, said means including elements which successively engage in alternation from above and below portions of the lace to be fed, and means for imparting an oscillating and reciprocating movement to said elements, said reciprocating movement being effected longitudinally of the lace.

3. In a device of the character described, the combination of a threading needle and means for feeding lace on the needle, said means including elements which successively engage in alternation from and below portions of the lace to be fed, and means for imparting an oscillating and reciprocating movement to said elements, said oscillating movement being effected transversely of the lace.

4. In a device of the character described, the combination of a threading needle, a lace feeding element adapted to project into the needle, and means for reciprocating said lace feeding element relatively of the needle.

5. In a device of the character described, the combination of a threading needle, a lace feeding element adapted to project into the needle, and means for reciprocating and oscillating said lace feeding element relatively of said needle.

6. In a device of the character described, the combination of a threading needle, a lace feeding element adapted to project into the needle, means for reciprocating said lace feeding element relatively of the needle, and means for adjusting the stroke of the feeding element.

7. In a device of the character described, the combination of a threading needle, a lace feeding element, and means for moving said feeding element cyclically through an elliptical path intercepting the plane of the needle.

8. In a machine of the character described, the combination of a threading needle, a shaft, means for rotating the shaft, feeding elements controlled by said shaft adapted to project into the needle, and means for converting the rotary movement of said shaft into a reciprocating movement for said feeding elements along said needle, the elements projecting into the needle in one part of their movement and being remote from it in another part of their movement.

9. In a machine of the character described, the combination of a threading needle, a shaft, means for rotating the shaft, feeding elements controlled by said shaft and adapted to project from opposite sides into the needle, and means for converting the rotary movement of said shaft into an oscillating movement for said feeding elements the feeding elements oscillating at opposite sides of the needle and at longitudinally spaced points.

10. In a machine of the character described, the combination of a threading needle, a shaft, means for rotating the shaft, feeding elements controlled by said shaft, a plurality of members mounted on said shaft and rotated therewith, and means connected with said members and said feeding elements for moving said feeding elements through elliptical paths at opposite sides of the needle and in opposite directions.

11. In a machine of the character described, the combination of a threading needle, a shaft, feeding elements, means for rotating the shaft, structures supported by said shaft and carrying the feeding elements, and means for permanently oscillating said supporting structures simultaneously in opposite directions.

12. In a machine of the character described, the combination of a threading needle, a shaft, means for rotating the shaft, feeding elements, structures supported by said shaft and carrying the feeding elements, and cams on said shaft engaged by arms secured to said structures and adapted to permanently oscillate said structures simultaneously in opposite directions.

13. In a machine of the character described, the combination of rotary shafts, lace feeding elements, yokes supporting said lace feeding elements, and pivotally carried by said shafts, arms pivoted to said yokes, and cams mounted on the rotary shafts engaged by said arms and adapted to impart an oscillating movement to said feeding elements.

14. In a machine of the character described, the combination of rotary shafts, lace feeding elements, yokes pivotally supported by said rotary shafts and carrying said lace feeding elements, and means on said shafts for reciprocating said lace feeding elements through said yokes. 70
15. In a machine of the character described, the combination of a rotary shaft, 75 a lace feeding element, a support for said lace feeding element in which the element is movably carried, means on the shaft for oscillating the support, and other means on the shaft for reciprocating the lace feeding 80 element through the support simultaneously with its oscillating movement.
16. In a machine of the character described, the combination of a rotary shaft, a lace feeding element, a yoke pivotally mounted on the shaft, a sleeve on said yoke, the lace feeding element extending through said sleeve, a means on said shaft for oscillating said sleeve, and another means on said shaft for reciprocating the feeding element through the sleeve. 85
17. In a machine of the character described, the combination of a rotary shaft, a lace feeding element, a yoke supported by said shaft, a sleeve on said yoke through 90 which the lace feeding element extends, a cam on the shaft, an arm on the yoke engaging said cam and adapted to oscillate the sleeve, a crank disk on said shaft, and a connection between said crank disk and said lace feeding element adapted to reciprocate said lace feeding element through said sleeve while the same is being oscillated. 95
18. In a machine of the character described, the combination of a pair of rotary 100 shafts, lace feeding elements associated with each of said shafts, yokes pivotally mounted on said shafts and by which said lace feeding elements are carried, means on said shafts for actuating said lace feeding elements, and means for normally forcing said lace feeding elements to inoperative position. 105
19. In a machine of the character described, the combination of a pair of shafts, 110 cooperating lace feeding elements, means controlled by said shafts for actuating said lace feeding elements, supporting structures for each of said lace feeding elements, each of said structures being mounted on one of said shafts, means for normally forcing said supporting structures to inoperative position, and means for moving both of said structures to operative position when one of said structures is being forced to said position. 115
20. In a machine of the character described, the combination of a pair of rotary shafts, lace feeding elements associated with each of said shafts, supporting structures for the lace feeding elements mounted on 120 said shafts, means controlled by said shafts for actuating said lace feeding elements, yokes pivotally supported by said rotary shafts and carrying said lace feeding elements, and means on said shafts for reciprocating said lace feeding elements through said yokes. 125
21. In a machine of the character described, the combination of a pair of rotary shafts, lace feeding elements actuated by said shafts, supporting structures for each of said lace feeding elements, means for forcing either one of said supporting structures to operative position when the other one is moved to said position, and means for limiting the movement of either of said supporting structures relatively to the other. 130
22. In a machine of the character described, the combination of a pair of rotary shafts, lace feeding elements actuated by said shafts, supporting structures for said lace feeding elements, means for normally maintaining said supporting structures in inoperative position with their lace feeding elements separated from each other in inoperative position, means for moving one of said supporting structures to operative position, means for moving the other supporting structure to operative position, said last named means being controlled by the first mentioned means, and an element for limiting the movement of said supporting structures towards each other. 100
23. In a machine of the character described, the combination of a pair of rotary shafts, lace feeding elements associated with said shafts, a pair of crank disks, one mounted on each shaft, adjustable crank slides movable on said disks, and means for connecting said slides to said lace feeding elements. 105
24. In a machine of the character described, the combination of a pair of rotary shafts, lace feeding elements associated therewith, disks mounted on said shafts, crank slides associated with said disks, elements for locking said slides in adjustable position on said disks, said slides being adjustable independently of each other, and means for connecting said slides with said reciprocating elements. 110
25. In a machine of the character described, the combination of a rotary shaft, lace gripping shoes, means controlled by said rotary shaft for reciprocating said gripping shoes, and means for guiding said gripping shoes in their reciprocating movement. 120
26. In a machine of the character described, the combination of a rotary shaft, a cross head, means controlled by said rotary shaft for imparting a reciprocating movement to said cross head, a pair of gripping 130

shoes secured to said cross head, and means for moving said gripping shoes in different planes to inoperative position.

27. In a machine of the character described, the combination of a rotary shaft, a pair of gripping shoes, means for yieldingly forcing said gripping shoes towards each other, means controlled by said rotary shaft for simultaneously reciprocating said gripping shoes, and means for swinging said gripping shoes simultaneously about axes disposed at an angle to each other.

28. In a machine of the character described, the combination of a rotary shaft, a cross head, means for reciprocating said cross head controlled by said rotary shaft, a pair of gripping shoes, means associated with one of said gripping shoes for moving it to operative and inoperative position, and means associated with the last mentioned means for simultaneously moving the other gripping shoe to operative or inoperative position, respectively.

29. In a machine of the character described, the combination of a rotary shaft, a cross head, means for reciprocating said cross head controlled by said rotary shaft, a pair of gripping shoes, means associated with one of said gripping shoes for moving it to operative and inoperative position, and means associated with the last mentioned means for simultaneously moving the other gripping shoe to operative or inoperative position, respectively, said means for moving the gripping shoes being independent of the means of moving the cross head.

30. In a machine of the character described, the combination of a rotary shaft, a cross head, means for reciprocating said cross head controlled by said rotary shaft, a pair of gripping shoes, means associated with one of said gripping shoes for moving it to operative and inoperative position, and means associated with the last mentioned means for simultaneously moving the other gripping shoe to operative or inoperative position, respectively, and means for locking said shoes in operative and inoperative position.

31. In a machine of the character de-

scribed, the combination of a rotary shaft, a pair of lace gripping shoes, a cross head from which said gripping shoes are supported, means controlled by said rotary shaft for reciprocating said cross head, means for forcing one of said gripping shoes yieldingly towards the other shoe and means for varying the force with which said shoe is urged towards the other shoe. 55 60

32. In a machine of the character described, the combination of a rotary shaft, a pair of lace gripping shoes, a cross head supporting said lace gripping shoes, means associated with the rotary shaft for reciprocating said cross head, a standard in which said cross head is guided, and means for locking said standard in adjusted position relatively of the rotary shaft. 65

33. In a machine of the character described, the combination of a threading needle provided with an eye near its point, a lace feeding element, and means for actuating said lace feeding element to intermittently enter and leave the eye of the 70 75 needle.

34. In a machine of the character described, the combination of a threading needle having an elongated eye near its point, a lace feeding element, and means 80 for imparting to said lace feeding element a movement in an elliptical path, said feeding element traveling through a portion of its path while it is moving within the eye of the needle. 85

35. In a machine of the character described, the combination of a threading needle having an elongated eye near its point, a pair of reciprocating feeding elements, and means for moving said feeding 90 elements above and below the point of the needle, each of said feeding elements having a portion of its path of travel located within the eye of the needle.

In testimony whereof, I affix my signature in the presence of two witnesses at 36 W. Randolph St., Chicago, Illinois. 95

HANS LUNDQUIST.

Witnesses:
